United States Patent Office

Des. 182,166
Patented Feb. 25, 1958

182,166

BILLFOLD

Herbert S. Chase, Woodmere, N. Y., assignor to Bernard Cahn Co., Inc., New York, N. Y.

Application June 24, 1957, Serial No. 46,715

Term of patent 7 years

(Cl. D87—3)

Fig. 1.

Fig. 2.

Fig. 3.

Fig. 4.

I claim:

The ornamental design for a billfold, substantially as shown.
